ROSWELL C. VAN SICKLE AND STANLEY T. SCHOFIELD, OF WILKINSBURG, PENNSYLVANIA, ASSIGNORS TO WESTINGHOUSE ELECTRIC AND MANUFACTURING COMPANY, A CORPORATION OF PENNSYLVANIA

OPERATING MECHANISM FOR OIL CIRCUIT INTERRUPTERS

Application filed December 9, 1927. Serial No. 238,756.

Our invention relates to circuit interrupters and particularly to operating mechanisms therefor.

One object of our invention is to provide an operating mechanism for circuit interrupters which shall be trip-free in all its positions.

Another object of our invention is to provide an actuating mechanism for a circuit interrupter that shall employ a latch and a magnetically-operated trigger that are in separate fixed pivoted positions.

A further object of our invention is to provide an operating mechanism for a circuit interrupter that shall be reset after the release of the interrupter.

A still further object of our invention is to provide an actuating mechanism wherein the maximum force exerted shall be effective at the time of the maximum magnetic repulsion between the movable and stationary contact members.

In designing circuit interrupters, in the past, attention has always been paid to obtaining some specific mechanical construction, such as trip-free protection, high speed of operation or strength of the various assembled levers.

According to our invention, we have provided a lever system for an operating mechanism that is trip-free, in operation, throughout its entire movement and, at the same time, that produces a structure that will open with a high speed and that may be operated to close the circuit interrupter in an efficient manner in accordance with the following description.

Referring to the drawings, Figure 1 is a view, partly in section and partly in elevation, of the particular embodiment of our invention in closed position.

Fig. 2 is a similar view, in elevation, in trip position immediately before the resetting of the trigger by gravity.

Fig. 3 is a view similar to that in Figs. 1 and 2 but showing the breaker in complete open position.

Our invention is embodied in an operating mechanism 1 which comprises an actuating solenoid 2 and a tripping solenoid 3, the latch

4 and the trigger 5 of which are pivotally supported in fixed positions.

The solenoid 2 is mounted upon a bracket 6 that is the means for pivotally supporting an actuating member 7 on pin 8. The actuating member 7 is connected by pin 9 and link 10 to the pin 11 that is pivoted to the moving core 12 of the solenoid mechanism 2.

A pin 13 on the end of the actuating member 7 opposite to the end pivoted to the pin 8, supports a floating lever 14 that is pivoted thereon. The floating link 14 has latching means 15 and 16 at its opposite ends for retaining it in fixed position, as will be described more fully hereinafter.

A pin 18, located near the mid section of the floating link 14, pivotally supports the connecting link 21, the other end of this link being connected by pin 22 to a rocker lever 23. The rocker lever 23 is rotatably supported on the extension 24 of the casing of the member 2 by a pin 25. Pins 26 and 27, at the ends of the operating lever 23, are the means of applying the force produced by the mechanism 1 to the apparatus to be operated. The pin 26 produces a downward pull, while pin 27, produces an upward pull. The apparatus is so arranged that either of such pulls may be utilized to close it.

A spring member 28 is connected to the rocker lever 23 by a pin 29. The member 28 is tensioned when the operating mechanism is in closed position and is employed to accelerate the rocker lever 23 to increase the speed of movement of the mechanism controlled thereby.

A bracket 31 on the solenoid mechanism 2 is the means for supporting the latch 4 in fixed pivotable position about a pin 32. A spring 33 is employed to bias the latch 4 in clockwise rotation. The latching means 15, comprising a projection on the floating link 14, engages a projection 34 on the latch 4 and is the means for retaining the operating mechanism 1 in closed position when the solenoid mechanism 2 is operated.

The latching means 16, on the end of the floating link 14 opposite to the latching means 15, comprises a pin 35, a link 36 and a bell crank 37. The bell crank 37 is pivotally

supported on the bracket 6 by a pin 38 and is connected, at its upper end, to link 36 by pin 39. A spring member 40 cooperates with one arm of the bell crank 37 to bias it in a clockwise direction. Arm 41 of the bell crank 37, opposite to the one pivoted to the pin 39, supports, at its end, a roller 42 that is designed to engage the re-entrant surface 43 of the magnetically-actuated trigger 5. By employing the bell crank 37 and the link 36, instead of directly latching the trigger 5 to the pin 35, we are able to obtain a very light latching load which will require a very small force to release.

The trigger 5 is pivoted to the tripping solenoid 3 by a pin 44 and is biased in a counter-clockwise direction by the spring mechanism 45. A projection 46 on the trigger 5 cooperates with a rod 47 on the moving core 20 of the said solenoid 3 and is the means, when the solenoid 3 is energized, for moving the trigger in a clockwise direction to release the latch 16.

A pin 48 on the actuating lever 7 supports one end of a link 49, the other end of which is pivotally supported on the pivotal member 51 by pin 54 and is the means for operating the mechanism 1 by hand. The pivotal member 51 is supported, by pin 52 on the solenoid mechanism 2 and contains projections for pivotal pins 53 and 54, to either of which the link 49 may be attached, depending upon the location of the operating mechanism 1 below or above the circuit interrupter supporting structure.

A tensioned spring 55 is suspended between a projection 56 on the solenoid mechanism 2 and the end 57 of the actuating member 7 to impart a counter-clockwise movement to the member 7 when the latch mechanism 15 is released.

Assuming the circuit interrupter to be in its closed position, as shown in Fig. 1, with the lug of the latching means 15 engaging the projection 34 of latch 4, and the roller 42 engaging the re-entrant surface 43 on the trigger 5, upon energizing the solenoid 3, the upward movement of the rod 47 strikes against the projection 46 of the trigger 5, thereby turning it in a clockwise direction. The re-entrant surface 43 of the trigger 5 is disengaged from the roller 42 and permits the bell crank 37 to turn in a counterclockwise direction, thus permitting the floating link 14 to move upward, rotating in a counterclockwise direction about the pin 13 and permitting the rocker lever 23 to move because of the action of the spring 28, to open the circuit interrupter. A further clockwise movement 60 of the floating link 14 releases the latching means 15, whereby the pin 13 becomes a floating pivot that permits the link 7 to move in a clockwise direction because of the tension in the spring member 55. This movement 65 causes the free end of the floating link 14 that

supports the pin 35, to move downward, moving the bell crank 37 first counterclockwise, then clockwise until such time as the roller on arm 41 thereof engages the re-entrant surface 43 of the latch 5, as shown in Fig. 3, at which time the mechanism is in its full-open position.

In closing the circuit interrupter, when the solenoid mechanism 2 is energized, as shown in Fig. 3, the moving core 12 is moved in a downward direction carrying with it the actuating lever 7, the floating link 14 and the link 21, which movement causes a clockwise rotation of the operating lever 23. The final movement of the moving core member 12 will move the lug of the latching means 15 into engagement with the projection 34 of the latch 4, retaining the mechanism 1 and the circuit interrupter in closed position after the deenergization of the solenoid mechanism 2.

If, at any time during the above-described closing operation, an overload or any other condition is present in the circuit in response to which the tripping solenoid 5 is arranged to be energized, the said energization will cause the floating link 14 to be released and permit the circuit interrupter to open, even though the energization of the solenoid 2 continued. This protection during closing is known in the art as a "trip-free" feature and the mechanism is known as a "trip-free mechanism".

In designing the above-described operating mechanism, special attention was given to the change in the effective length of the levers during operation, in order that the pull exerted by the mechanism 1 shall be increased to a maximum at substantially the end of two thirds of its closing movement, this being substantially the time at which the bridging member first comes into engagement with the contact members. Thereafter, the change in the effective lengths of the levers diminishes the amount of pull exerted by the mechanism 1, thus preventing slamming of the moving parts at the end of the closing movement of the circuit interrupter.

It is well known in the circuit interrupter art that a magnetic force acts on the bridging member when it engages the contact members, this force being due to the effect of the current traversing the said bridging member. In circuits carrying large currents, this blowout effect becomes quite appreciable. Heretofore, the operating mechanisms for circuit interrupters were designed in such a manner that the pull tending to close the circuit interrupter was a maximum at the end of its closing movement. This was undesirable for, if the solenoid was of such strength as to insure a closure where heavy current was flowing in the circuit, the final movement to closed position produced a slamming of the moving parts. If the force exerted by the closing mechanism reaches its maximum value when

the bridging member comes into engagement with the contact members, sufficient force will be exerted to assure the complete engagement of the said members and the harmful slamming will be eliminated because thereafter the force diminishes in value. Our above-described lever system operates to produce such a maximum pull as has just been described by the varying of the effective length 10 of the rocker lever 23 relative to the direction of the applied force through the link 21.

Accordingly, we have invented an operating mechanism for a circuit interrupter that is trip-free in operation in all positions, and 15 that employs a stationary pivotally supported latch and electrically actuated trigger so designed as to produce a high speed separation of the contact members.

By employing our present link arrangement, we obtain an operating mechanism in 20 which the maximum force is exerted at the time the maximum magnetic repulsion acts on the bridging member of the circuit interrupter. The bell crank link employed on the 25 tripping lever avoids a direct trigger engagement with the said lever, thus eliminating heavy trigger loads and enabling the operating mechanism to be released at any 30 position without the expenditure of a large amount of energy.

It is to be understood that such changes in the form, arrangement and connection of the component parts of our invention may be made as shall fall within the scope of the 35 appended claims.

We claim as our invention:

during tripping operation and the other to retain the entire mechanism in latched position.

5. In a circuit interrupter, the combination with a solenoid having pivotal means of support for a contact-carrying lever and for an actuating lever, of means for uniting the levers comprising a link and a floating lever and latching means for retaining the said floating lever in fixed relation with the actuating lever and with the solenoid. 75

6. In a circuit interrupter, the combination with a solenoid having pivotal means of support for a contact-carrying lever and for an actuating lever, of means for uniting the levers comprising a link and a floating lever and latching means in fixed position on the solenoid for retaining the floating lever in fixed relation with the actuating lever and with the solenoid. 80

7. In a circuit interrupter, the combination with a solenoid having separate means of support for a contact-carrying lever and an actuating lever, of means for uniting the levers comprising a link and a floating lever and latching means for retaining the floating lever in fixed relation with the actuating lever and with the solenoid. 90

8. In a circuit interrupter, the combination with a solenoid having separate means of support for a contact-carrying lever and an actuating lever, of means for uniting the levers comprising a pair of hinged link members, the one link member having an extension, and a pair of fixed pivotal latch members, one of which engages the said extension retaining it in fixed position while the actuating lever is operated to move the other end of the said link into engagement with the other said latch. 95

9. The combination with an actuating device, of a pair of levers pivoted thereto, a pair of connected links joining the said levers, a stationary latch, and a stationary trigger for governing the movement of the 100 said levers.

10. The combination with an actuating device, of a pair of levers pivoted thereto on separate supporting members, a pair of connected links joining the said levers, a stationary latch, and a stationary trigger for governing the movement of the 110 said levers.

11. The combination with an actuating device, of a pair of levers pivoted thereto on separate supporting members, a pair of connected links joining the said levers, a stationary pivotal latch, and an electrically-actuated stationary pivotal trigger for releasing the levers in any of their positions. 120

12. In a circuit interrupter, the combination with an operating mechanism and separable contact-carrying members, of a lever system cooperating with the contact carrying members and actuated by said operating mechanism and means in the said lever sys- 125

1. In a circuit-closing device, the combination with two pivotally mounted members, of a floating link hingedly supported at one 40 of its ends to one end of a pivotal member, latching means for each end of the said floating link and a link member for uniting the floating member to the other said pivotal member.

2. In a circuit-closing device, the combination with two pivotally mounted members, of a floating link hingedly supported at one 45 of its ends to one end of a pivotal member and a pair of stationary pivoted latches for retaining the above said members in fixed position.

3. In a circuit-closing device, the combination with two pivotally mounted members, of a floating link hingedly supported at one 55 of its ends to one end of a pivotal member and a pair of latches in fixed pivotal position for engaging each end of the said floating link.

4. In a circuit-closing device, the combination with two pivotally mounted members, of a floating link hingedly supported at one 60 of its ends to one end of a pivotal member and a pair of latches in fixed pivotal position, one for releasably engaging one end of the said floating link in all positions except

tem to vary the effective length thereof in order that the maximum force exerted by the operating mechanism occurs substantially at the time the said contact members touch.

5 13. A switching equipment in which large currents are present resulting in a blow-out effect produced when a circuit is being completed by the bridging member coming in contact with the contact members, an operating mechanism cooperating therewith and a system of levers so associated with the operating mechanism that a maximum force is produced substantially at the beginning of the said blow-out effect.

10 14. A switching equipment in which large currents are present resulting in a blow-out effect produced when a circuit is being completed by the bridging member coming in contact with the contact members, an operating mechanism cooperating therewith, and a system of levers associated with the operating mechanism that vary in effective length with relation to the effort exerted by the operating mechanism for producing a maximum force substantially at the instant of contact between the bridging member and the said contact members.

15 15. In a switch mechanism having separable contact members designed to carry heavy current and in which a blow-out effect is produced when the said contact members touch on closing, an actuating mechanism for operating the separable contact member, a lever system cooperating with the actuating mechanism characterized by means for producing a maximum force substantially at the time the said contact members touch.

20 16. In a switch mechanism having separable contact members designed to carry heavy current and in which a blow-out effect is produced when the said contact members touch on closing, an actuating mechanism for operating the separable contact member, a lever system cooperating with the actuating mechanism designed to be trip-free in all of its positions, said lever system being characterized by means to move the contact member in a manner such as to provide a varying force that increases to a maximum substantially at the instant the contacts come into engagement and that decrease thereafter.

25 17. In a circuit-interrupter operating mechanism, the combination with two pivotally mounted members, of a system of links for interconnecting the said members and a plurality of retaining means pivoted to fixed supports for engaging the said members when in a predetermined position.

30 18. In a circuit-interrupter operating mechanism, the combination with two pivotally mounted members, of means for interconnecting the said members and a pair of latches pivoted to fixed supports for engaging the said members when in a predetermined position.

In testimony whereof, we have hereunto subscribed our names this 5th day of December, 1927.

ROSWELL C. VAN SICKLE.
